COMBINED LADDER AND SCAFFOLD

Norbert Wick, Kiel, Wis.

Application February 15, 1940, Serial No. 319,166

2 Claims. (Cl. 304—3)

My invention is an improved construction of combined ladder and scaffold of that particular type in which the parts include a pair of ground wheels and are adapted to be folded one upon another for convenience in moving the apparatus from place to place.

The principal object of my invention is to provide an apparatus of this general character which will be especially useful in gathering fruit, whereby in picking fruit from the top of a tree the parts can be arranged to support the ladder in a substantially upright position, and in picking fruit from the body of the tree the ladder can be readily swung to a horizontal position and braced to form a scaffold or raised platform on which the fruit gatherer may stand and on which baskets or other containers for the fruit may be placed.

A further object of my invention is to provide a knockdown ladder and scaffold supported in connection with a hand truck to not only facilitate transporting it from one place to another in knock-down condition but also facilitate movement of the apparatus around the tree whether arranged in the form of a ladder or scaffold.

With these principal objects in view my invention contemplates a construction in which the body of the hand truck constitutes one of the essential elements in supporting the ladder in either upright or horizontal position, in association with additional braces for the ladder or platform, the several parts being so connected that they may be folded together for transportation in the same manner as a wheeled hand truck.

My invention therefore contemplates combining a ladder with the framework of a hand truck in combination with bracing elements cooperating to support the ladder in either upright or horizontal position, as hereinafter fully described and more specifically set forth in the appended claims.

In the drawings:

Fig. 1 is a perspective view showing the apparatus arranged in the form of a ladder disposed and supported in substantial upright position.

Fig. 2 is a front elevation of Fig. 1.

Fig. 3 is a view illustrating the parts arranged to form a scaffold.

Fig. 4 is a side elevation showing the parts folded for transportation, and

Fig. 5 is a detail view of one of the pivotal connections.

In carrying out my invention I provide a main supporting frame 10, similar in construction to a wheeled hand truck, with spaced apart side pieces, 11, connected by crosspieces and having the ground wheels 12 mounted on an axle 13 5 journaled in bearing boxes 14 secured to the under side of the side pieces at one end thereof, the outer ends of the side pieces being shaped to form hand grips, 15. To near the outer ends of the side pieces of this supporting frame a ladder 16 of usual construction is pivoted by a long bolt 17, and in order to space the projecting ends of the side pieces or hand grips thereof a sufficient distance apart to permit a person to walk between the same in transporting the apparatus 15 from one place to another, filling blocks 18 are interposed between said side pieces of the supporting frame and sides of the ladder. The pivotal connection of the ladder to the wheeled frame is such that when the ladder is in substantially upright position, as shown in Fig. 2, the lower end thereof will rest on the ground with the side pieces of the frame inclined slightly upward from the ground wheels, and for supporting the ladder in this position a back frame or 20 brace 19 extends from the inner end of the main supporting frame to the upper portion of the ladder, said back frame or brace being made up of spaced apart strips pivotally connected at their upper ends to the sides of the ladder from which they diverge and are pivotally connected at their lower ends between the side pieces of the main frame by bolt 20, with crosspieces 21, 21 connected to the ends of the strips for maintaining their spaced apart relation. Attached to 25 one of these crosspieces are outwardly projecting blocks 22, 22 disposed at an angle to the back frame and adapted to support the ladder and back frame on the wheel supporting frame in the manner hereinafter described. To provide for 30 folding the brace when the ladder is lowered on the truck for transportation it is made in two sections joined by hinges 23, with crosspieces 24, 24 extending between the strips at opposite sides of the break joint. The connection of the foldable back frame to the main supporting frame is preferably by means of a long bolt similar to the bolt connection of the ladder to said supporting frame, whereby the ladder and associated supporting frame may be readily disconnected 35 from the wheeled truck for use of either the ladder or truck for other purposes, it being necessary only to remove the two bolts.

The construction so far described provides simple and effective means for supporting the ladder 55

in upright position in those situations where it is 5 inconvenient or impossible to support the upper end of the ladder against the trunk of a tree, wall, or other object, and by connecting the parts in the manner hereinbefore described the ladder may be folded down on the supporting frame of the wheeled truck with the folded back frame resting on the blocks 22, 22 so that the rearwardly projecting portion of the ladder will be a 10 sufficient distance above the ground when the forward end of the truck is raised in wheeling it from place to place.

For supporting the ladder in a horizontal position so that the apparatus may be used as a scaffold 15 for any purpose, as for instance in harvesting a crop from fruit trees, the ladder is provided at each end with a pair of props 25 and 26, more especially to prevent sidewise movement of the platform, it being apparent that the main frame 20 and bracing frame which extend from the axle of the supporting wheels will be constructed of material of sufficient stability to support the platform in horizontal position. The props are all connected to the ladder so that they may be 25 swung rearwardly and laterally, and for this purpose the metal fixture illustrated in Fig. 5 is employed, consisting of an attaching plate 27 having a lateral member 28 to which is swiveled a U-shaped connection 29 to which the prop is 30 pivoted.

From the foregoing description of the construction and operation of the combined ladder and scaffold in accordance with my invention it will be apparent that when the parts are arranged 35 with the ladder in upright position the lower end thereof will be supported against movement in any direction by the main frame having the ground wheels spaced apart to a greater extent than the side pieces of the ladder and the upright position maintained by the back frame. In this position the ladder may be used for various 40 purposes, and in converting the apparatus to a scaffold it is only necessary to swing the ladder to a horizontal position when the main frame 45 and back frame will extend from the axle of the wheels at opposite inclinations therefrom, and by positioning the props at both ends of the ladder at an outward inclination from the ladder or platform they will steady the scaffold to 50 thereby provide a structure having the required stability for various uses for which an apparatus of this character is desired.

In arranging the parts for transportation the props 25 at the outer ends of the ladder or plat-

form are brought on a line with the side pieces thereof and held in place by any suitable means, as for instance by hooks, and as the ladder or platform is lowered the jointed back frame is folded so that said frame and the ladder will rest on the blocks 22 and crosspieces 21, the props 26 being then supported by hooks 30 depending from one of the last mentioned crosspieces. The several parts of the apparatus are then arranged in compact form on the wheeled frame for moving the apparatus from place to place. 10

I claim:

1. A combined ladder and scaffold adapted to be knocked down or folded for convenience in transportation, comprising a main supporting 15 frame having connected side pieces supported at one end by ground wheels from which they converge toward their outer ends, a ladder pivoted to the main frame near the outer ends of the side pieces from which the latter project in the form 20 of hand grips, a jointed back frame for supporting the ladder in substantially upright position and consisting of sections hinged together and connected at opposite ends to the ladder and main frame, and props swiveled to each end of the 25 ladder at opposite sides thereof for use in bracing the ladder when arranged to form the platform of the scaffold.

2. A combined ladder and scaffold adapted to be knocked down or folded for convenience in 30 transportation, comprising a main supporting frame having connected side pieces supported at one end by ground wheels from which they converge toward their outer ends, a ladder pivoted to the main frame near the outer ends of the side 35 pieces from which the latter project in the form of hand grips, a long bolt forming the pivotal connection between the ladder and main frame, a jointed back frame for supporting the ladder in substantially upright position and consisting of 40 sections hinged together and connected at opposite ends to the ladder and main frame, the pivotal connection with the main frame being by means of a long bolt extending through the side pieces of the main frame and jointed frame, props 45 swiveled to each end of the ladder at opposite sides thereof for use in bracing the ladder when arranged to form the platform of the scaffold, and hooks attached to the main frame and ladder for connecting the free ends of the props thereto 50 when the parts are folded on the wheeled frame for transporting the apparatus from one place to another.

NORBERT WICK.
